R. F. GREENWOOD.
CIGAR AND CIGARETTE HOLDER.
APPLICATION FILED DEC. 10, 1921.

1,425,498.

Patented Aug. 8, 1922.

UNITED STATES PATENT OFFICE.

RICHARD F. GREENWOOD, OF BROOKLYN, NEW YORK, ASSIGNOR TO APEX
SPECIALTIES CORPORATION, A CORPORATION OF NEW YORK.

CIGAR AND CIGARETTE HOLDER.

1,425,498.

Specification of Letters Patent. Patented Aug. 8, 1922.

Application filed December 10, 1921. Serial No. 521,358.

To all whom it may concern:

Be it known that I, RICHARD F. GREENWOOD, a citizen of the United States, and a resident of the borough of Brooklyn, in the county of Kings, city and State of New York, have invented certain new and useful Improvements in Cigar and Cigarette Holders, of which the following is a specification.

This invention relates to improvements in cigar and cigarette holders, and particularly to the type of such holders that are adapted to eject the unconsumed end or butt of a cigar or cigarette.

One of the objects of this invention is to produce a holder which may with greater ease and facility than has heretofore been possible be separated and cleaned and reassembled by the user and which is formed of a minimum number of parts.

Another object of this invention is to produce a holder of symmetrical and pleasing appearance which may be made of relatively short length and small diameter; in which all the operating parts are enclosed in a casing and the outer surface will be substantially smooth and without sharp corners.

Another object of my invention is to produce a butt-ejecting holder in which the plunger will have effective sliding surfaces engaging opposite ends of the casing.

Another object of my invention is to produce an effective air-tight seal between the parts of the holder when the same are in normal position.

Another object of my invention is to provide effective means for locking in place an ornamental band at the outer end of the holder.

Another object of my invention is to provide a relatively long spring enclosing space to enable the use of a stronger and longer spring in a holder of a given length and I preferably provide for such a large spring space without decreasing the extent of sliding surface.

With these ends in view, I produce a holder composed of a mouth-piece and an ejecting plunger preferably formed integrally to reduce the number of parts; a spring receiving sleeve, a spring arranged between the plunger and sleeve and a removable end-receiving cap for the sleeve adapted to enclose and tension the spring. I also preferably provide between the combined mouth-piece and plunger on the one hand

and the casing on the other hand, a plurality of spaced interengaging sliding surfaces and a stop seat which produces an effective air-tight seal between the parts when the same are in normal positions, thus preventing side play or wobbling between the parts.

With these and other objects in view, the invention comprises the combination of members and arrangement of parts so combined as to coact and cooperate with each other in the performance of the functions and the accomplishment of the results herein contemplated, and comprises in one of its adaptations the species or preferred form illustrated in the accompanying drawings, in which:

Fig. 1 is a central longitudinal section of a holder embodying my invention, with the parts of the holder in a position for receiving a cigarette or cigar;

Fig. 2 is a similar section view of my improved holder with the parts in position for ejecting the unsmoked end or butt of a cigarette or cigar;

Fig. 3 is an end view of the holder shown in Figs. 1 and 2; and

Fig. 4 is a cross-section on the line 4—4 of Fig. 1;

Fig. 5 is a view of the parts of my holder in disassembled condition;

Fig. 6 is a fragmentary view of the tip or cap and adjacent sleeve portion showing the method of locking an ornamental band in place; and

Fig. 7 is a section on the line 7—7 of Fig. 2.

Referring now to these drawings, which illustrate a preferred embodiment of my invention, my improved holder comprises a relatively stationary casing 1 comprising a spring encircling sleeve 2 having a smooth parallel bore 3 adapted, as hereinafter stated, to form, in part, a sliding surface and contracted in diameter at its rear end 4 to provide a stop shoulder 5 and a reduced parallel bore 4^a. The bore 3 at the forward end 6 of the sleeve 2 is of greater diameter so as to permit a relatively movable member 7 to be inserted through such front end 6 and to stop against said shoulder 5. Said movable member 7 comprises integral mouth-piece and plunger stem portions 8 and 9 respectively, and has intermediate its ends an integral sliding ring 11 of increased diameter and a stop shoulder 10 adapted to 110

engage and abut against the stop shoulder 5 of the sleeve 2 to limit the rearward movement of the members 1 and 2 respectively. Said shoulders 5 and 10 are preferably disposed at right angles to the axes of the respective parts to produce an effective airtight seal when the parts are in normal position and retained in close abutment by a spring hereinafter specified. The external 10 surface of the ring 11 which is located adjacent to the end of the sleeve 2 when the parts are in normal position engages and has a sliding fit with the rear end of the internal bore 3 of the sleeve 2, and the bore 15 4^a also preferably slidably engages a portion of the circumference of the stem portion 8. Said plunger portion 9 is also reduced in diameter as at 12 to form a space 13 for enclosing a spring 14 and also to provide an abutment 15 for one end of the 20 spring 14. Said plunger portion is also preferably further reduced in diameter at 16 to provide, in addition to its function of providing space for the spring, an elongated 25 sliding surface adapted to slidably fit within and engage the interior wall 17 of a cigarette-receiving bore 18 of a tip or cap 19 and also to provide a stop shoulder 16^a adapted to abut against the end 19^a of the 30 tip or cap 19 to limit the forward movement of the parts. The tip or cap 19 is adapted to close the space between the sleeve and plunger at the forward end and to apply 35 initial tension on the enclosed spring 14 so as to secure the aforesaid air tight seal between the shoulders 5 and 10, and is, as illustrated, provided with an elongated external threaded portion 20 which engages with the internal threaded portion 21 of the 40 sleeve 2.

In many cases it is desirable to place an ornamental band 24 of gold or other material contiguous to the forward end of the holder and in my improved holder I am enabled effectively to position and insert such a band in the holder merely by providing a seat in two halves 23, 23^a therefor at the outer end of the sleeve and between such sleeve and the tip, so that the screwing on 45 of the tip will cause a locking of the band in place and will give a finished appearance to such a banded holder.

All the parts of this device, except the spring, are adapted to be composed of bakelite, hard rubber, meerschaum, seasoned wood or other suitable material or composition and it will be seen that I have provided a holder which may be made relatively small, slender and of pleasing appearance and 50 which will provide a large enclosed spring space to enable the use of a relatively long and effective spring for the device and furthermore all side play or wobbling between the parts is prevented by providing effective sliding surfaces at opposite ends of the

sleeve portion. In fact, when the holder is in ejecting position there are three sliding surfaces between the sleeve and movable member 7, viz, at each end and in the middle thereof.

It will furthermore be apparent that I have produced a holder which may be readily disassembled for cleaning and in which all of the parts are simple and inexpensive to manufacture, and furthermore that I 70 produce a holder in which the movable part may be inserted through the front end of the relatively stationary part, the spring may be then set in place with a considerable portion projecting beyond the sleeve, as 75 shown in Fig. 5, and when the threaded tip is then applied, the spring will be initially compressed and the space between the plunger and sleeve will be closed and at the same time a sliding engagement and fit with the 80 forward end of the plunger will be produced. The draft bore 22 extends through the mouth-piece and plunger and communicates with the cigarette-receiving bore of the tip or cap 19. The draft through the 85 bore will, therefore, be applied directly at the end of the cigarette or cigar without any loss of such draft or any looseness between the parts. Furthermore the movable member may be moved to effectively eject a 90 cigarette butt from the tip 19 when the cigarette has been consumed.

The employment of a relatively short end or tip portion which is connected to the holder enables the replacement of the tip in 100 the event of a destruction or partial burning thereof by the leaving of a burning cigarette or cigar therein.

Having described my invention, I claim:—

1. In a cigarette or cigar holder, the combination with a relatively stationary spring-enclosing sleeve having a relatively large bore and a bore reduced in diameter to provide a stop shoulder between the front and rear ends of the sleeve; of a relatively movable member having a draft bore, said movable member comprising a mouth-piece at the rear end portion, an extension ring portion intermediate the ends forming a stop shoulder adapted to engage said stop shoulder of the sleeve, and a plunger portion at the forward side of said ring portion so reduced in diameter as to provide a spring-enclosing space between said plunger-stem and sleeve, a spring arranged in the space 110 between said plunger and sleeve, and a removable tip adapted to close the space between the plunger and sleeve, and to form an abutment for one end of the spring.

2. A cigarette holder embodying, in combination, a two-piece outer member, comprising a sleeve and an end-receiving cap removably secured thereto, said outer member having between its ends a bore increased in diameter and at each end of said in- 115 120 125 130

- creased bore having a communicating bore reduced in diameter, one of which contracted bores is formed in the sleeve and the other in the removable cap; and a one-piece 5 inner member releasably retained in sliding engagement with the outer member by said cap, and comprising a mouth-piece and plunger having a draft bore; said inner member having between its ends a portion 10 increased in diameter to fit within the said enlarged bore in the outer member and to be releasably confined therein by said removable cap.
3. A cigarette holder embodying, in combination, a two-piece outer member, comprising a sleeve and an end-receiving cap removably secured thereto, said outer member having between its ends a bore increased in diameter and at each end of said increased bore having a communicating bore reduced in diameter, one of which contracted bores is formed in the sleeve and the other in the removable cap; and a one-piece inner 20 member releasably retained in sliding engagement with the outer member by said cap, and comprising a mouth-piece and plunger having a draft bore; said inner member having between its ends a portion increased in diameter to fit within the said 25 enlarged bore in the outer member and to be releasably confined therein by said removable cap, and a spring abutting at one end against the enlarged portion of the inner member and at the other end against the 30 cap.
4. In a cigarette or cigar holder, the combination with a relatively stationary spring-enclosing sleeve having a screw-threaded end, a relatively large bore extending from 35 said screw-threaded end toward the opposite end, and a bore reduced in diameter at said opposite end to form a stop shoulder between such bores; of a relatively movable member having a draft bore and insertible through the said screw-threaded end of said sleeve; said movable member comprising a mouth-piece at the rear end portion, an extension ring portion intermediate the ends forming a stop shoulder adapted to engage 45 said stop shoulder of the sleeve, and a plunger portion of reduced diameter at the forward side of said ring portion to provide a spring-enclosing space between said plunger-stem and sleeve, a screw threaded cap engaging the threaded end of said sleeve 50 and a spring arranged under compression between said cap and said ring portion.
5. In a cigarette or cigar holder, the combination with a relatively stationary sleeve having a relatively large bore extending 55 from the front end toward the rear end and a bore of reduced diameter at said rear end forming a stop shoulder therebetween, of a relatively movable member having a draft bore and insertible through the front end 60 of said sleeve; said movable member comprising a mouth-piece at one end portion, an extension ring portion intermediate the ends forming a stop shoulder adapted to engage said reduced rear end of the sleeve, 65 and a plunger portion at the forward side of said ring portion, and a tip adapted to close the space between the plunger and sleeve, said tip and sleeve being provided with interengaging screw threads and an ornamental ring arranged between said sleeve and said tip to permit a fastening thereof by the connection of the tip to the sleeve.
- . In witness whereof, I have signed my name to the foregoing specification in the 70 presence of two subscribing witnesses.

RICHARD F. GREENWOOD.
